UNITED STATES PATENT OFFICE

ROBERT T. ROMINE, OF MOUNT CLEMENS, MICHIGAN

PORTABLE STACK LIFTER

Application filed August 1, 1927. Serial 209,833.

This invention relates to a portable stack lifter or crane capable of being propelled through relatively low doorways or where restricted overhead room is provided. This 5 stack lifter is particularly adapted to be carried into or out of a freight car and is constructed to lift heavy loads from the floor of the car onto a truck platform or other conveying medium, or vice versa.

10 An object of the invention is to provide a stack lifter of the foregoing character capable of having its height increased to enable it to handle loads of abnormal size.

Another object of the invention is to provide 15 the stack lifter supporting leg structure with means to be engaged by a lift truck platform for increasing the height of the stack-lifter, such means likewise serving to support the stack lifter so that it may be transported upon the lift truck platform.

Other objects of this invention will appear 20 in the following description and appended claims, reference being had to the accompanying drawings forming a part of this specification wherein like reference characters designate corresponding parts in the several views.

In the drawings:

Fig. 1 is a side elevation of the stack lifter 25 or crane embodying my invention with the parts in their relative normal positions.

Fig. 2 is an end elevation of the construction shown in Fig. 1.

Fig. 3 is a view similar to Fig. 1 showing 30 the stack lifter in its elevated or adjusted position.

Fig. 4 is an end elevation of the stack lifter of Fig. 3.

Fig. 5 is a section taken along the line 5, 5 35 of Fig. 3.

Before explaining in detail the present invention, and the method or mode of operation embodied therein, it is to be understood that the invention is not limited in its application to the details of construction and arrangement of parts illustrated in the accompanying drawings, since the invention is capable of other embodiments and of being practiced or carried out in various ways. 45 Also it is to be understood that the phrase-

ology employed herein is for the purpose of description and not of limitation, and it is not intended to limit the invention beyond the terms of the several claims hereto appended or the requirements of the prior art. 55

The portable stack lifter or crane embodying my invention is shown as a whole at V and comprises a substantially arch-shaped frame having four spaced side supports or legs, such as a pair of front legs A and a similar pair of rear legs A¹. Each leg or support is preferably identical in construction, comprising a pair of front and rear parallel structural steel angle bars 10 and 11 respectively. 60

The top frame of the stack lifter comprises a pair of end transverse angle bars 12 and a pair of longitudinal side angles 13. To provide an intermediate floor or supporting frame located below the top frame, transverse channel bars 14 at the front and rear 65 ends of the stack lifter and longitudinal channels 15 at opposite sides of the frame work, are provided. The vertical leg members 10 and 11 and the members 12, 13, 14, and 15 are rigidly connected together by means of gusset plates 16 and 17 provided on opposite sides and ends, respectively, at the top of the frame 70 work of the stack lifter. Housed within the frame work at the upper end is the hoisting mechanism, including reduction gearing, lifting drums and an electric motor, all of these last-mentioned parts being shown and described in my co-pending application Serial No. 133,374, filed September 3, 1926. The 75 stack lifter is provided with a pair of lifting bars or members B which support at opposite ends sheaves or pulley wheels C. Cables D pass about the sheaves C and are adapted to be wound upon the winding drums E. In order to lift and lower the bars C, the electric 80 motor M is operated and serves to wind or release the cables D through the medium of the hoisting mechanism above referred to. A control lever G is provided for the purpose 85 of supplying or cutting off the electric current for operating the motor.

Each angle 11 is provided with a bracket 18 and a guide member 19 preferably in the form of an angle and having vertically aligned 90 guide holes through which extends the verti- 100

cal stem 21, of a lifting dog 20, this stem being provided with a plurality of holes or apertures 21^a. A removable pin 22 carried by each bracket is adapted to enter any one of the apertures 21^a to maintain the lifting dogs 20 in adjusted position.

The lower ends of the side supports or legs A and A¹ are preferably provided with extensions F comprising a pair of relatively large channel members 23 and 24 the overlapping flanges of which are preferably secured together by means of rivets. The leg extensions or channels are connected together in pairs by means of a metal bar or connecting member 25 provided with pairs of holes or apertures at opposite ends. These bar and leg extensions are releasably secured in vertically adjusted position to the legs A and A¹ by means of pins 34 insertable through any of the pairs of holes 10^a and 11^a. A foot or base portion for each leg extension is provided and comprises preferably a metal plate 24^a bent into substantial U-shape and secured to the web of the channels 23 and 24 by means of rivets 26.

For the purpose of supporting the stack lifter when not under load to permit it to be propelled or wheeled about, spring supported caster wheels 27 and 28 are provided. Each front caster wheel 27 is supported by means of a bracket 29 carried by the front leg extension F and each rear caster wheel 28 is mounted upon a pivoted arm 30 connected with the lower end of the rear leg extension F. The caster wheel 27 is normally urged downwardly into contact with the ground by means of a coil spring 27^a. The caster wheel 28 is maintained normally in contact with the ground by means of a spring 28^a surrounding a rod or stem 31 carried by the forward end of the pivoted arm 30 and slidably connected with the member 25 at its upper end through the medium of a bracket 32.

From the foregoing it will be seen that the slideable leg extensions F together with the interconnecting bar 25, support the spring pressed caster wheels of the stack lifter.

The lower ends of the vertical angles 10 and 11 of the forward and rear leg members are provided with a series of holes or apertures 10^a and 11^a.

When it is desirable to increase the height of the stack lifter, it is merely necessary to move an industrial truck T having an elevating or lift platform L into position between the spaced legs of the stack lifter as shown in Fig. 2. The lifting dogs 20 are then brought into engagement with the top of the lift platform and held in adjusted position by means of the pins 22. The pins 34 carried by the members 25 are released, and the platform L elevated to move the legs A and A¹ of the stack lifter upwardly relatively to the leg extensions F until the desired height of

the stack lifter has been reached, whereupon the pins 34 are replaced and maintain the parts in their adjusted positions. The distance between the vertically spaced holes 10^a and 11^a preferably corresponds to the range of lift of the lift truck platform. The lifting dogs 20 are then swung laterally toward each other and out of engagement with the lift platform L and are returned in this inoperative position by means of the pins 22 which are inserted thru apertures 21^b (Fig. 2) extending thru the stems 21 at right angles to the apertures 21^a. Thereupon the lift truck T is backed out and the stack lifter is in readiness for use. The reverse of this operation is employed to decrease the height of the stack lifter.

In Figs. 1 and 2 I have shown the stack lifter in its normal position of use with the legs and extensions telescoping so that the lower ends of the legs A and A¹ engage the web or base portion of the plates 24^a. In Figs. 3 and 4 I have shown the stack lifter in an elevated or extended position the lower ends of the legs A and A¹ being shown by the dotted lines 100.

The present stack lifter is particularly adapted to be carried into and out of a freight car on the lift platform L of the truck T. Owing to the fact that the freight car doorways have a certain maximum overhead clearance the normal height of the stack lifter is determined by the height of the car doorway. This invention however permits the stack lifter to be carried thru such doorways and the height of the stack lifter to be increased within the car so as to increase the height of the crane bay beneath the hoisting mechanism thereby permitting loads or packs of abnormal height to be lifted from the car floor.

What I claim is:

1. A portable stack lifter comprising an arched frame having legs spaced to permit the introduction therebetween of a lift truck platform, hoisting mechanism carried at the top of the frame, telescopic extensions carried by the lower ends of said legs for permitting the height of the stack lifter to be varied, caster wheels mounted on said extensions, and adjustable lifting dogs carried by said legs and adapted to overlie said truck platform.

2. In a portable crane, an arched frame having depending pairs of vertical legs, each leg comprising a main section and a telescopic section one located within the area of the other, a bar rigidly connecting each pair of telescopic leg sections at a side of the frame, a caster wheel structure supported by the bar and telescopic sections, and means carried by the main leg sections adapted to cooperate with a lifting device to enable the frame to be lifted vertically and to permit adjustment of said telescopic sections.

3. In a portable crane, an arched frame having spaced pairs of legs, a bar connecting a pair of legs and slidable vertically thereon, leg extensions carried by said bar and slid-
5 able vertically therewith, and a pair of wheel carrying supports carried by said bar.
4. In a portable crane, an arched frame having spaced pairs of legs, a bar connecting a pair of legs and slidable vertically thereon, leg extensions carried by the bar, and a
10 spring mounted wheel carrying support connected to a leg extension and yieldable vertically relatively to said bar.
5. In a portable crane, an arched frame having spaced pairs of legs, a bar connecting a pair of legs, a wheel carrying support piv-
15 oted to a leg beneath said bar, and a spring between said support and bar to resist swing-
ing movement of the support relatively to
20 the bar.
6. In a portable crane, an arched frame having depending pairs of legs spaced to pro-
vide a crane bay, a bar connecting each pair
of legs and slidable vertically relatively
25 thereto, leg extensions connected to said bar,
and slidable vertically therewith, devices
carried by said legs above the bar and leg ex-
tensions and adjustable into position to co-
30 operate with a lifting means to enable the
frame to be lifted or lowered vertically there-
by to permit adjustment of said leg exten-
sions.

In testimony whereof I affix my signature.
ROBERT T. ROMINE.
